[57] ABSTRACT

An improved imaging chamber for an electron radiographic system with a d.c. potential and an a.c. potential in the radio frequency range connected across the electrodes to provide increased current collection while reducing interelectrode discharge problems.

ELECTRON RADIOPHGRAPHIC IMAGING CHAMBER WITH CURRENT ENHANCEMENT

This invention relates to the creation of X-ray images without the use of conventional X-ray film, sometimes referred to as ionography. In particular, it relates to the technique described in the copending application of Muntz, et al, Ser. No. 261,927, filed June 12, 1972, entitled Radiographic Systems with Xerographic Printing, and assigned to the same assignee as the present application. In such a system, an X-ray opaque gas at high pressure (e.g. 20 atmospheres) is used between two electrodes in an imaging chamber to produce a photoelectric current within that chamber as a function of X-rays entering the chamber. The current is collected on a dielectric sheet placed on one or the other of the electrodes, resulting in a latent electrostatic image on the sheet. The latent image is then made visible by xerographic techniques. Collection of the primary photoelectrons created by the X-rays absorbed in the inter-electrode gas filled gap and of the secondary electrons created by collisions of the primaries with the gas atoms is achieved by use of an accelerating potential difference, typically of the order of 5,000 volts, applied between the electrodes.

The value of the applied d.c. potential between the anode and cathode is selected in the above system so as to satisfy two constraints. On the one hand, the applied accelerating field or potential should be as high as possible so as to maximize the current or total electron count produced per absorbed X-ray quantum. The higher the collected charge, the more readily the latent electrostatic image can be made visible, e.g. by powder cloud development, because the fields controlling toner particle deposition are clearly proportional to charge on the receptor, and at very weak fields other forces on the toners (e.g. aerodynamic forces) and random momentum of toner particles lead to random toner deposition and therefore poor imaging. In addition, at higher charge levels the effects of stray charge collected on the receptor (both before and after the exposure), which acts as a source of noise, and is the limiting factor in contrast resolution, becomes less important. Also, at very weak fields the rate of toner deposition for toner that is controlled by the imaging fields becomes too slow for practical use of the system. By these criteria one would even want to operate the device in the so-called electron avalanche region of the Townsend discharge curve, in which significant current gains over the primary photoelectric current are possible. However, as the accelerating potential is increased, the operation of the ionization chamber becomes increasingly unstable, leading in particular to localized discharges, generally aggravated by the presence of small foreign particles (dirt, lint and so forth) within the imaging chamber. Indeed, unless particular care is taken to keep the chamber free of such foreign particles, discharges and attendant discharge spots in the resultant image occur at values of the accelerating potential well short of full collection potential V_c , (where V_c may be defined as that value of the potential at which substantially all the primary and secondary electrons created by photoelectric absorption of the X-rays are collected at the receptor). More correctly, the controlling quantity, which determines the collected current, is the accelerating field divided by the pressure p , i.e., the quantity E/p , rather than the voltage $V = (E/p)pd$,

where d is the gap width. Current collection in the imaging chamber is discussed more fully below.

Early onset of discharge spots due to foreign particles results from the field concentrations and effective reductions in electrode spacing which occur when a particle of dirt, or of lint, or other substance is placed in the interelectrode gap. Such particles therefore reduce the value of the applied potential at which localized breakdown would otherwise occur. Typically, the potential at which discharge spots appear is reduced from 5,000 Volts to 3,000 or 4,000 V, for typical operating conditions of the imaging chamber, in going from a relatively clean to a relatively dirty chamber. When great pains are taken to maintain chamber cleanliness, discharge free operation is possible at voltages up to 7,000 to 8,000 volts, which is typically the full collection potential. In operation at 3,000 V, the current collected can be half the full collection current, at high X-ray energies.

Experimentally, it is found that the local electron avalanche leading to discharges builds up in times of the order of a few up to a few hundred microseconds, whereas X-ray exposure durations in medical radiology last anywhere from milliseconds to several seconds. There is therefore no way to avoid such discharges by restricting the time during which the accelerating potential is applied, since the time during which it must be on is much longer than the time required for the discharge to develop.

Thus, in the prior art devices, one must compromise, in choosing the operating value of the accelerating potential, between maximizing the collected charge for a given exposure level, which leads as explained above to a more easily developed and less 'noisy' visible image, and keeping the accelerating fields which collect the current to low enough values so as to avoid discharge spots which constitute diagnostically damaging image deletions, without having to go to extreme lengths to prevent any foreign matter from entering the imaging chamber.

Accordingly, it is an object of the present invention to provide a means for increasing the current and collected charge on the insulating receptor of the electronradiographic imaging chamber resulting from an absorbed X-ray quantum without resulting in unstable operation and localized discharges and discharge spots. It is also an object of the invention to make the performance of the imaging chamber less sensitive to dirt, and therefore to enhance the practical usefulness of electron radiography.

This new and improved performance is achieved by augmenting the applied steady or d.c. accelerating or current collecting electric field in the imaging chamber with an a.c. field which does not itself collect current but does increase the number of electrons collected by the d.c. field, at any given value of the latter, above the number that would result in the absence of the a.c. field.

Other objects, advantages, features and results will more fully appear in the course of the following description. The single figure of the drawing illustrates an electron radiographic system with imaging chamber and incorporating the presently preferred embodiment of the invention.

X-rays are directed from a source 10 past the object 11 being X-rayed to the imaging chamber 12, which

may be conventional in design such as set out in the aforementioned copending application.

A typical imaging chamber includes a housing 13 carrying a cathode 14 on an insulator 15, with an anode 16 carried on another insulator 17. The dielectric sheet receptor 18 may be carried on the anode, with gas introduced into the chamber at 19 filling the gap between the electrodes.

A d.c. field is produced across the gap by a d.c. supply connected at terminal 25 and coupled to the anode 16 through an RF choke coil 26 and a coupling inductance 27, with the cathode 14 connected to system ground.

The a.c. field is provided by a radio frequency oscillator 30 connected to the grid of a power amplifier triode 31, with the amplifier energized from the B+ supply and with the RF output coupled through the inductance 27 to the anode 16, with a variable capacitor 32 connected across the triode for RF tuning.

The basis for the enhancement achieved with the system of the drawing can be understood from the following qualitative description of the physical processes occurring in the imaging chamber 12. Consider the events following the absorption of a photon by photoelectric absorption in the K or L shell of one of the Xenon atoms in the gas gap. The resulting ejected electron, which has an energy typically of a few tens of kilovolts, produces a trail or swarm of secondary electrons by impact ionization of other Xenon atoms, which lose electrons from their outer shells. The swarm of secondary electrons, which are rapidly thermalized, then drifts towards the collecting electrode under the influence of the applied field. The drift velocity of the electrons is approximately proportional to the applied field. In their drift, the electrons gain energy from the field, and lose energy in elastic and inelastic collisions with the gas molecules. The electrons can also recombine with the ions present in the gas, either directly or more frequently by attachment to a neutral molecule followed by negative ion-positive ion recombination. Recombination is the only effective loss mechanism of the secondary electrons under the high pressure conditions of operation of the imaging chamber.

At low values of the applied field, the electron (and negative ion) drift velocity is low, and the energy gained by the electrons from the field per unit length of travel in the direction of the field is low, so that a majority of the secondary electrons produced in the swarm are lost by recombination before they reach the collecting electrode. As the applied potential is increased, the electron drift velocity increases while the probability of recombination (and attachment), which is strongly dependent on electron energy, decreases because of the increased energy gained from the field by the electrons between collisions. Thus the collected current increases, until there comes a point, at what we have called full collection potential V_c , when essentially all the secondary electrons are collected, and a so-called plateau is reached in the current voltage characteristic, where further increases in accelerating potential do not result in increased current.

The above description is an oversimplification in that it omits another process which occurs in the gas, namely the increase in the number of electrons in a swarm due to inelastic collisions of the electrons with neutral molecules in the gas, which result in the creation of additional ion pairs. In fact, the ionization and

recombination are competing processes, and the former increases with applied field (and therefore field strength) just as the latter decreases with increasing applied field. Ionization becomes significant well before recombination is reduced essentially to zero, and indeed there is no true plateau in collected current, but rather a very slow increase with increased voltage.

Beyond a certain value of the applied potential, the rate of ionization exceeds the rate of recombination and there is a net gain in collected current. This is the so-called avalanche regime in which each initial secondary electron leads to collection of more than one electron at the receptor.

As the applied voltage is increased into the avalanche region, secondary processes begin to appear which result in creation of electrons by the action of photons created by the collision processes and by other effects, which lead to more avalanching, followed by further creation of electrons and so forth, so that the discharge becomes effectively self sustaining. This is the phenomenon of breakdown, occurring at the breakdown value V_b of applied potential. Since the electron avalanche and secondary creation processes are random in nature, isolated breakdowns will occur randomly in localized regions of the chamber before the point of full breakdown of the gas in the gap has been reached. When foreign particles are present, they will tend to increase the field strengths in their vicinity, and therefore lead to the same effect as if the applied field had been increased, namely localized breakdown, resulting in discharge spots in the developed image. These can be avoided by reducing the applied field to the point where even the local enhanced fields are not sufficient to produce breakdown. However, as this is done, one suffers a loss in collected current, because of the direct or indirect recombination losses described above.

It has been found that the recombination losses can be eliminated or reduced by increasing the average electron energy without increasing the applied accelerating field, since recombination rates fall off very sharply with electron energy. This can be done by radio frequency energy to pump energy into the free electron gas in the chamber. Such a procedure will be very effective in permitting full current collection, since an increase in mean electron energy to only 1 electron volt, requiring typically a power dissipation of 10^{-5} watts/cm³ of imaging chamber, or about 10^{-2} watts total for a typical chamber image area, assuming a modest pumping efficiency of 10^{-3} , will reduce the recombination rate by one to two orders of magnitude. The use of high radio frequency fields in the 10 MHz to 100MHz region appears to be the most practical and efficient. If frequencies significantly below 1 MHz were used, the applied a.c. field would act much as an addition to the steady field, with respect to breakdowns, since the formation of breakdown avalanches have characteristic times of the order of microseconds. On the other hand, at frequencies above 10^9 Hz, which corresponds to a wavelength of 30 cm, field nonuniformities over the dimensions of the imaging chamber would become significant. At laser frequencies, coupling of power to the electron gas would become quite inefficient, and in any event there is nothing to be gained by going to such high frequencies. Indeed, the criteria for selecting frequencies are, at the lower end, that the imposed fields should not appear as d.c. fields with respect to the breakdown phenomenon, and at the upper

end that uniform enhancement, and therefore uniform fields, and effective coupling to the free electron gas be achieved.

These criteria lead to the choice of the 10 MHz to 100 MHz frequency range. The effective a.c. field strength E required for an applied a.c. field E_0 is simply

$E = E_0(1 + \omega^2/v^2)$ where ω is the angular frequency of the applied field and v is the electron collision frequency. For the case of interest here, $\omega \leq 10^{10}$ rad-sec $^{-1}$, $v > 10^{12}$ Hz, so that $E \sim E_0$. To obtain the required enhancement, field strengths of 10,000 volts/cm or less are required, and these are readily achieved. Note that by use of a.c. fields, it becomes possible to operate the imaging chamber somewhat into the avalanche region (i.e., to induce electron multiplication in the a.c. field) and thereby achieve gains in current beyond the full collection current. However, the a.c. field must be kept to values below those at which it would itself induce gas breakdown. It is interesting that the threshold for a.c. breakdown will in fact be raised by the presence of the d.c. field which inhibits local electron breakdown. Thus the d.c. and a.c. fields aid each other in terms of permitting full current collection and possibly amplification without breakdown. Typical values for the tandem fields would be, in terms of the applied potential differences around 3,000 volts for the d.c. potential, and around 3,000 volts (r.m.s.) for the a.c. potential. The d.c. potential may be reduced to as low as 1,000 volts, or

be as high as 10,000 volts for large gas gaps (> 1 cm), while the a.c. potentials may also range as low as 1,000 volts and as high as 10,000 volts.

I claim:

1. In an electron radiographic system, the combination of:

an imaging chamber having spaced electrodes with a gas filled gap there between;
a means for connecting a d.c. potential and an a.c. potential across said electrodes to produce an electric field in said gap having a steady state collecting component and an oscillating ionizing component.
2. A system as defined in claim 1 including means for generating said a.c. potential in the range of about 10^6 Hz to about 10^9 Hz.
3. A system as defined in claim 1 including means for generating said a.c. potential in the range of about 10^7 Hz to about 10^8 Hz.
4. A system as defined in claim 1 including:

a d.c. power supply;
a radio frequency oscillator; and
a radio frequency amplifier energized from said d.c. supply;
with said oscillator connected as an input to said amplifier and with said amplifier output connected to said electrodes providing said d.c. and a.c. potentials.
